(57) **CLAIM**

The ornamental design for a centripetal telescope that uses a laser for surveying instrument, as shown and described.

DESCRIPTION

FIG. 1 is a perspective view of a centripetal telescope that uses a laser for surveying instrument, showing my new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view showing a state in which a cap is placed;

FIG. 8 is a left side elevational view showing a state in which a cap is placed; and,

FIG. 9 is a reference view showing the state of use thereof; The broken line showing the remaining parts of a support base for a laser light range meter equipped with a telescope is for illustrative purposes only and forms no part of the claimed design.
